UNITED STATES PATENT OFFICE.

FRANK LAMBERT, OF BROOKLYN, NEW YORK.

FAN.

1,090,481.

Specification of Letters Patent. Patented Mar. 17, 1914.

Application filed July 25, 1910. Serial No. 573,679.

To all whom it may concern:

Be it known that I, FRANK LAMBERT, a citizen of the United States, and a resident of Brooklyn, county of Kings, and State of New York, have invented certain new and useful Improvements in Fans, of which the following is a specification.

My invention relates to improvements in fans, particularly of the type employed for producing circulation of air in warm weather, which fans are usually driven by small electric motors. It is common to impart to such fans, in addition to their rotary motion, a bodily oscillation about a single axis—usually a vertical or nearly vertical axis. According to my present invention I so mount and drive the fan that it has not only an oscillation about this vertical or nearly vertical axis, but also an oscillation about a horizontal or nearly horizontal axis; and specifically, the fan has a bodily oscillation of a nutatory type. Thereby the breeze from the fan is caused to cover a much larger area than is practicable when a fan oscillates about a single axis only, and other desirable results are accomplished.

The objects of my invention are to improve fans of the class described, to cause the breeze from them to cover a larger area effectively than is practicable when the fan oscillates about a single axis only, and to make the mechanism by which the compound oscillation is effected, simple, compact, inexpensive and reliable.

The compound motion given to the fan, according to my invention, is accomplished by mounting the fan pivotally in an oscillatory support itself pivotally mounted, the pivotal axis of such support being at an angle to the axis of oscillation of the fan about such support,—such angle being usually a right angle, and by providing suitable driving mechanism whereby the fan is caused to oscillate about both of these axes, besides having its usual rotary motion.

I will now proceed to describe my invention with reference to the accompanying drawings, illustrating one embodiment thereof, and will then point out the novel features in claims.

In said drawings: Figure 1 shows a front elevation of one form of fan embodying my invention; Fig. 2 shows a side view of the supporting and driving mechanism of the fan, including the motor; Fig. 3 shows a rear elevation of the same parts; Fig. 4

shows a detail sectional elevation of one form of reducing driving gear which may be employed for imparting to the fan the compound oscillation characteristic of my present invention; Fig. 5 is a detail front view of the frame member provided with the guide for the pivot-pin of the mechanism which oscillates the fan. Fig. 6 shows a vertical section of the reducing driving gear, on a plane at right angles to that of Fig. 4, and Fig. 7 shows a horizontal section of such driving gear also on a plane at right angles to that of Fig. 4.

In the drawings, 1 designates the fan-wheel or propeller-wheel of my improved fan; 2 the driving motor thereof, which may be of any usual type, the particular motor illustrated being an electric motor, though I do not limit myself to the use of any particular type of motor.

3 designates the spindle of the motor, upon which spindle or driving shaft the fan wheel 1 is mounted for rotation.

4 designates a carrying ring to which the motor is pivoted by pivot screws 5, for oscillation about a horizontal or nearly horizontal axis.

6 designates a frame member to which the carrying ring 4 is pivoted by means of a pivot screw 7 and pivot pin 8, for oscillation about a vertical or nearly vertical axis. In the particular construction shown, the angle of the carrying ring 4 to the vertical is adjustable, the frame member 6 being curved approximately circularly for the greater portion of its length, and being adjustably mounted in a base 9, so that it may be shifted with respect to said base, thereby varying the angle of the axis 7—8 with reference to the vertical. This latter detail of mounting the curved frame 6 adjustably mounted in the base 9, is not in itself a feature of my invention, being a feature of construction of one well known type of fan.

It will be clear that by imparting to the motor 2, and so to its driving shaft 3 and the fan wheel carried thereby, an oscillation about the axis 5—5 and also an oscillation about the axis 7—8, a compound oscillation is imparted to the fan wheel, in addition to its regular rotary motion, such oscillation being specifically of the general nature of a nutatory motion. It will be apparent that because of this compound oscillation given to the fan, the breeze from the fan will sweep over a much larger area than if the

fan oscillated about a single axis only. Also, since the compound oscillation is progressive the breeze from the fan will have a sweeping action different from that of a 5 fan oscillating about a single axis only, and better adapted for producing a general circulation of air in a room.

Various forms of mechanism may be employed for imparting to the fan, mounted as 10 above described, a motion of rotation or oscillation about its two axes of support. I do not limit myself to any particular mechanism for the purpose, but have illustrated one such mechanism, well adapted for the 15 purpose and comprising a planetary reducing gear comprising an externally-toothed planet gear wheel 13 (Fig. 4), driven by the driving shaft 3 of the fan motor, as hereinafter described, and intermeshing with an 20 internal gear 12 within a case 10 mounted on a crank arm 11 (Fig. 2) provided with a pin 19 the end of which engages slot 20 in frame member 6. An eccentric 14 is mounted upon the motor spindle 3 and revolves 25 within a bearing at the center of the planetary gear 13, and thereby imparts a rolling motion to the planetary gear 13 with reference to internal gear 12, whereby the planetary gear 13 is caused to roll around within 30 the gear 12; and since said gear 13 has a less number of teeth than has gear 12, the result of this rolling motion of the planetary gear is to impart a slow rotation to gear 13 with reference to its own axis. Such 35 rotation of the gear 13 is communicated to case 10 through a spider 15 having lugs 16 engaging other lugs 17 carried by the case 10 and having further lugs 18 having a sliding connection with gear 13, through being mounted in notches in the rim of said 40 gear 13. The rotary motion thus imparted to case 10 causes the crank arm 11 to revolve about its pivot 19, so imparting a lateral oscillation, *i. e.*, an oscillation about axis 45 7-8, to the motor and fan, by reason of the lateral throw of the crank during its rotation, and also imparting a vertical oscillation to the motor, *i. e.*, an oscillation about the axis 5-5, by reason of the up and down 50 throw of the crank in its rotation.

The particular planetary reducing gear above described is a gear which is well known in numerous connections, among others in connection with electric fans for 55 imparting thereto an oscillatory motion about a single axis, but has not been used heretofore to my knowledge for imparting a compound oscillation to a fan.

The pivot pin 19 of the crank arm may 60 travel up and down in a groove 20 formed in the frame member 6, between stops 21 and 22 adjustably mounted upon said frame member; or, said stops may be set so close together as to prevent any such longitudinal

motion of the pivot pin. By varying the 65 distance apart of these stops, the degree of up and down oscillation of the fan may be varied at will. The pivot pin 19 may be set at various points along the crank arm 11, a plurality of apertures 23 being provided in 70 this crank arm for this purpose, and thereby the degree of oscillation of the motor about the vertical or nearly vertical axis, *i. e.*, the axis 7-8, as well as the degree of oscillation about the horizontal axis, may be 75 varied at will. But I do not limit myself to the particular means illustrated for varying the degree of oscillation about either axis.

The fan may be provided with the usual 80 fan-guard 24, which, being carried by the motor 2, as is customary in electric fans, will oscillate with said motor and therefore need be no larger than the guards of ordinary electric fans.

While I have illustrated my fan as mounted upon a pedestal base, it will be obvious that it may be mounted in various ways. It is well adapted, for example, for use as a ceiling fan, being suspended from the ceiling, in which case the axis 7-8 will customarily be horizontal or nearly so, the axis of rotation of the driving shaft or spindle 3 of the motor being then vertical or nearly so.

It is obvious that the details illustrated 95 and described above for supporting the motor for bodily oscillation or rotation about a plurality of axes, and for imparting such oscillation to the motor, may be varied very greatly without departing from the spirit 100 and scope of my invention, which is not limited to any such details as are illustrated and described.

By changing the position in the same direction of both of the sliding stops 21 and 105 22, I can vary the field of nutatory oscillation of the fan.

What I claim is:

1. A fan comprising in combination a fan-wheel, a motor for driving the same, 110 a carrier to which said motor is pivoted, a support to which said carrier is pivoted, a crank, the free end of which is mounted to move with bodily movement of said motor, and reducing transmission mechanism im- 115 parting motion from said motor to said crank.

2. A fan comprising in combination a fan-wheel, a motor for driving the same, a carrier to which said motor is pivoted, a 120 support to which said carrier is pivoted, a crank, the free end of which is mounted to move with bodily movement of said motor, the pivot of said crank mounted for motion in a restrained path, and transmission mech- 125 anism driven by said motor arranged to impart motion to the crank.

3. A fan comprising in combination a

fan-wheel, a motor for driving the same, a carrier to which said motor is pivoted, a support to which said carrier is pivoted, said support having in it a guide groove, 5 a crank, the free end of which is mounted to move with bodily movement of said motor, said crank having a pin mounted to move in said guide groove, adjustable means limiting the motion of such pin in said 10 groove, and transmission mechanism driven

by said motor and arranged to impart motion to said crank.

In testimony whereof I have signed this specification in the presence of two subscribing witnesses.

FRANK LAMBERT.
